(57) **CLAIM**

The ornamental design for a handheld game device, as shown and described.

DESCRIPTION

FIG. 1 is a front perspective view of a handheld game device showing the new design;

FIG. 2 is a front elevation view thereof, shown with game pieces removed for complete disclosure;

FIG. 3 is a back elevation view thereof, shown with game pieces removed for complete disclosure;

FIG. 4 is a left-side view thereof, shown with game pieces removed for complete disclosure;

FIG. 5 is a right-side view thereof, shown with game pieces removed for complete disclosure;

FIG. 6 is a top plan view thereof, shown with game pieces removed for complete disclosure;

FIG. 7 is a bottom plan view thereof, shown with game pieces removed for complete disclosure;

FIG. 8 is a top-right perspective view thereof, shown with game pieces removed for complete disclosure; and,

FIG. 9 is a bottom-right perspective view thereof, shown with game pieces removed for complete disclosure.

1 Claim, 9 Drawing Sheets
